(57) **CLAIM**

The ornamental design for a bath chair for infants, as shown and described.

DESCRIPTION

FIG. 1 is a front and top perspective view of a bath chair for infants showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof; and,

FIG. 8 is an enlarged view of the bath chair for infants taken from the circle part in FIG. 1.

The dashed broken lines circles in FIG. 1 and FIG. 8 define the bounds of the enlargements and do not form part of the claimed design.
